UNITED STATES PATENT OFFICE.

JOSEPH CORWEL, OF BELLOWS FALLS, VERMONT.

DESIGN FOR A SCRUBBING-BRUSH.

56,584.

Specification for Design.

Patented Nov. 16, 1920.

Application filed February 4, 1920. Serial No. 356,242. Term of patent 3½ years.

To all whom it may concern:

Be it known that I, JOSEPH CORWEL, a citizen of Poland, and a resident of Bellows Falls, in the county of Windham and State of Vermont, have invented a new, original, and ornamental Design for a Scrubbing-Brush, of which the following is a specification, reference being had to the accompanying drawing, forming part thereof.

The figure is a front view of a scrubbing brush showing my new design.

I claim—

An ornamental design for a scrubbing brush, as shown.

JOSEPH CORWEL.
